UNITED STATES PATENT OFFICE

95,054

DESIGN FOR A SHOE HEEL

Fred C. Lovejoy, St. Louis, Mo., assignor to United
Shoe Machinery Corporation, Paterson, N. J., a
corporation of New Jersey

Application January 8, 1935, Serial No. 54,771

Term of patent 14 years

To all whom it may concern:

Be it known that I, Fred C. Lovejoy, a citizen
of the United States, residing at St. Louis, in the
State of Missouri, have invented a new, original,
and ornamental Design for a Shoe Heel, of which
the following is a specification, reference being
had to the accompanying drawing, forming part
thereof.

In the drawing,
Fig. 1 is a view in side elevation of a shoe heel
embodying my new design; and
Fig. 2 is a bottom plan view of the shoe heel.
What I claim is:

The ornamental design for a shoe heel, as
shown.

FRED C. LOVEJOY.
